UNITED STATES PATENT OFFICE

RICHARD ORFORD, OF ST. JOSEPH, MICHIGAN.

WASHING-MACHINE.

SPECIFICATION forming part of Letters Patent No. 330,848, dated November 17, 1885.

Application filed July 24, 1885. Serial No. 172,547. (No model.)

To all whom it may concern:

Be it known that I, RICHARD ORFORD, a citizen of the United States, residing at St. Joseph, in the county of Berrien and State of Michigan, have invented certain new and useful Improvements in Washing-Machines; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 Figure 1 is a longitudinal vertical section. Fig. 2 is a transverse vertical section. Fig. 3 is a perspective view of the removable inner frame and the oscillating frame, showing the bearings detached from the main frame; and 20 Fig. 4 is a perspective view of a portion of the main frame.

An important desideratum in this class of machines is to apply to the clothes being treated a sufficient and varying pressure, and 25 to do this conveniently is a feature of the invention.

Referring to the drawings, A designates the tub or main frame, of semicircular form, supported on legs a, and having vertical side 30 standards, A'. These standards A' have upon their inner sides vertical recesses a', in which are preferably fitted castings a², having at their lower ends journal-bearings a³, which receive the gudgeons or journals d of the oscillating 35 frame D. This latter frame or rubber D is composed of the ordinary corrugated slats and end pieces, is of a form corresponding to that of the tub, and is provided with an operating-handle, as D'.

40 B designates a frame composed of end pieces held in rigid relation to each other by cross-arms, two of which are arranged in the upper portion, and are marked x x.

Journaled upon the pins b³, located upon 45 each end of the presser-frame B, are rollers b, and these rollers operate loosely in the recesses a' in the standards A', as seen in Fig. 2, and serve to allow vertical motion in the said slots, at the same time holding the frame B against 50 partaking of the reciprocating motions of the rubber.

Upon either side of the frame B is secured

a bracket, B', at the lower end of which is a saddle, b², which, when the frame B is at its lowest point, rests upon the gudgeons d, as 55 seen in Figs. 2 and 3.

Journaled in the end pieces of the frame B, and located between such end pieces, are corrugated rollers C, the shafts of which are shown at e, and these rollers are arranged in 60 the arc of a circle corresponding to that described by the rubber and tub.

In my construction I deem it important that the rollers C are journaled in bearings which are stationary in so far as the reciprocations 65 of the rubber are concerned, but movable vertically with the frame B.

I attach importance to the saddles b² and their supports for maintaining a proper relation between the rubber and the rollers, absolutely precluding the possibility of their coming in contact when in use, but allowing the rollers to ride over an accumulation of clothes whenever necessary.

I attach importance to the fact that the rubber oscillates between the tub and the rollers, and that pressure exerted upon the frame B with one hand of the operator serves, through the saddles b², to hold the rubber-journals d in the lower portion of the recesses a' as the said 70 rubber is operated by the other hand. In my device one of the rubbing-surfaces—that of the rollers—occupies but a small portion of the area of the tub, allowing the operator to frequently and easily handle the clothes being 75 treated, allowing clothes to be taken out and put in without disturbing the frame B. When the rubber is removed from the tub, the frame B is removed with it. The clothes are not allowed to come in contact with the journals. 80 85 90

I am aware of Patent No. 66,686, in which the rollers are journaled in the rubber-frame and the tub has a corrugated bottom. I am also aware of Patent No. 165,598, in which a flexible rubber operates between the tub and 95 a movable frame; but in such construction the clothes being operated upon are not open to the free vision or manipulation of the operator, and the features of importance in my construction—viz., rollers C, bracket B, rollers b, 100 and saddles b²—are absent. My rubber has an oblique handle, D', which extends over adjacent to the bars x x of the frame B, allowing the operator to nicely adjust the pressure

while operating the rubber. The bracket B', having the pins b^3 and saddle b^2 , is a single casting.

What I claim as new is—

- 5 1. In combination with the main frame or tub A, having standards A' with recesses a' , the presser-frame B, having rollers C and friction-roller b, and the rubber D, having oblique handle D', and gudgeons d, operating in the said recesses a' , to oscillate between the presser-frame and tub, as set forth.
- 10 2. In a washing-machine, substantially as described, the combination, with the tub A, having castings a^2 , and the rubber D, having 15 gudgeons d, of the presser-frame B, having

rollers b, casting B', and saddles b^2 , as and for the purposes set forth.

3. In a washing-machine, as described, the casting B', having pins b^3 and saddle b^2 , secured to the frame B, and having rollers b upon said pins b^3 , in combination with the tub A, having recesses a' , and the rubber D, having gudgeons d, as set forth. 20

In testimony whereof I affix my signature in presence of two witnesses.

RICHARD ORFORD.
